DESIGN FOR A HAND MIRROR

Morris Salinger, Brooklyn, N. Y., assignor to Duranol Products, Inc., Brooklyn, N. Y., a corporation of New York

Application January 5, 1945, Serial No. 117,267

Term of patent 7 years

(Cl. D86—10)

To all whom it may concern:

Be it known that I, Morris Salinger, a citizen of the United States, residing at Brooklyn, in the county of Kings and State of New York, have invented a new, original, and ornamental Design for a Hand Mirror, of which the following is a specification, reference being had to the accompanying drawing, forming part thereof.

The side of the mirror, not shown, is substantially like the side shown in the drawing.

I claim:

The ornamental design for a hand mirror, substantially as shown and described.

MORRIS SALINGER.
